UNITED STATES PATENT OFFICE

BERGER STOCKFLETH, OF BERRIEN SPRINGS, AND FREDERICK W. BURGER, OF NILES, MICHIGAN, ASSIGNORS TO CLARK TRACTOR COMPANY, OF BATTLE CREEK, MICHIGAN, A CORPORATION OF MICHIGAN

PORTABLE CRANE

Original application filed February 9, 1925, Serial No. 7,946. Divided and this application filed April 16, 1928. Serial No. 270,232.

Our invention relates to hoisting mechanism, such as cranes and has for one of its objects to provide improved hoisting mechanism especially adapted for use on a portable crane. Other objects of our invention are to provide an improved hoisting mechanism in which the hoisting chain is moved positively in either direction, regardless of whether or not it carries a load, and one in which the bight of the chain is always maintained taut so that any stretching of the chain is compensated for and it properly engages at all times with the sheaves over which it operates. We accomplish our objects as illustrated in the drawings and as hereinafter described. What we regard as new is set forth in the claims.

In the accompanying drawings,—

Fig. 1 is a side elevation of our improved crane attachment, showing it applied to the front portion of a tractor to which it is attached, and which furnishes power to operate the hoisting mechanism, certain parts being broken away and some parts being in section;

Fig. 2 is a diagrammatic view illustrating the arrangement of the hoisting chain with reference to the sheaves over which it runs;

Fig. 3 is a front elevation of the crane attachment and the tractor with which it is associated;

Fig. 4 is an enlarged detail, being a cross-section on line 4—4 of Fig. 1;

Fig. 5 is an enlarged detail, being a cross-section on line 5—5 of Fig. 1 but showing parts that are broken away in Fig. 1; and

Fig. 6 is an enlarged detail, being a partial section on line 6—6 of Fig. 4.

Our improved crane attachment and the hoisting mechanism thereof are of the type shown and described in our pending application, Serial No. 7,946, filed February 9, 1925, of which application this is a division. In the illustrated construction our crane attachment is adapted to be applied to a motor vehicle or shop tractor of the internal combus-

tion engine driven type, but it is to be understood that our improved hoisting mechanism is not limited to use with such a vehicle, but may be used in any situation to which it is adapted. As shown in Fig. 1, the crane attachment comprises a yoke or U-shaped frame 7 disposed horizontally and adapted to be associated with the front of a tractor frame. Only the dashboard 8 and front dirigible wheels 9 of the tractor are shown, as the tractor itself has nothing to do with our present invention. The side members 10 of the attachment frame are adapted to be connected with the tractor frame in any suitable way, preferably such as that illustrated in our above-mentioned application.

The yoke 7 is supported at the sides of the tractor by caster wheels 11 mounted in yokes 12, as shown in Fig. 3, said yokes being provided with vertical spindles journaled in suitable bearings mounted in sleeves 13 at the opposite ends of the intermediate portion of the yoke 7. As shown in Figs. 1 and 3, said sleeves are integral with the yoke.

Mounted on the central portion of the yoke 7 is an upright mast or jib 14, as shown in Figs. 1 and 2, said mast being preferably composed of two parallel curved angle irons 15, 16 that are disposed oppositely to each other, their vertical flanges being on the inside, as shown in Fig. 3. Said angle irons are braced by an upright curved plate 17 secured at its lower end to the yoke 7, as shown in said figure, and connected to said angle irons by bolts 18. At the upper end of the mast 14 is a transverse shaft 19, as shown in Fig. 1, which carries a sheave 20 arranged between the angle irons 15, 16 and adjacent to one of said angle irons, preferably the angle iron 15, 16, as shown in Fig. 3. In the same vertical plane as the sheaves 20 is another sheave 21 that is located adjacent to the lower end of the mast and is mounted on and keyed to a transverse shaft 22 journaled in suitable bearings 23, 24 supported by the

angle irons 15, 16, as shown in Fig. 3. Preferably the sheave 21 is secured to the shaft 22 by a pin 25 that passes through the hub 26 of said sheave and through said shaft. One end of the shaft 22 extends out through the bearing 24 and operatively engages a tubular shaft 27, best shown in Fig. 3, by which it is operatively connected with a shaft (not shown) on which a worm wheel 28, a portion of which is shown in Figure 1, is non-rotatably secured. The worm wheel is enclosed in a housing 29 that is mounted on one of the sleeves 13, as shown in Figs. 1 and 3, and in the lower portion of said housing is a worm 30 mounted on a shaft 31 which in the illustrated construction is adapted to be aligned substantially with a power take-off shaft on the tractor frame driven from the internal combustion engine of the tractor, as described in my above-mentioned application. As the power take-off shaft and its connections with the engine have nothing to do with our present invention it has been deemed unnecessary to show or describe them herein.

25 The mast 14 also carries a bracket 32 located near its upper end, as shown in Fig. 1, said bracket being located between the angle iron members 15, 16 and being secured thereto by cross bolts 33, 34. Mounted on said 30 bracket are two transversely disposed shafts 35, 36. The shaft 35 loosely supports an intermediate sheave 37 that is in the same vertical plane as the sheaves 20 and 21, and is provided with a laterally extending hub 38 on 35 which is loosely mounted a sheave 39, as best shown in Fig. 4. Between said sheaves 37, 39 is a coiled spring 40, one end of which bears against a laterally projecting lug 41 carried by the sheave 37, and the other end 40 of which bears against a laterally projecting lug 42 carried by the sheave 39, as best shown in Fig. 6. By this arrangement the spring 40 functions as a resilient power transmitting device by which power may be transmitted 45 from the sheave 37 to rotate the sheave 39 in one direction, and, conversely, power may be applied by the sheave 39 to the sheave 37 to rotate the latter in the opposite direction.

50 The shaft 36 carries an idler sheave 43, preferably smaller in diameter than the sheaves 37, 39, and lying in the same vertical plane as the sheave 39, as shown in Fig. 5. All of the sheaves referred to are of the type adapted to be used in connection with a hoisting chain 44, their chain engaging surfaces being of such design as to engage the links of the chain and hold the chain against slippage, as clearly shown in Figs. 4 and 5. The course of the hoisting chain 44 is best shown 55 in Fig. 2, from which it will be seen that that end of the chain to which the load is attached, and which preferably is provided with a hook 45, or other convenient means for attaching it to a load, hangs pendent from the sheave 60 20 over which the chain runs. It then passes

over sheave 37, down around sheave 21, thence up over sheave 43, and then around sheave 39, the adjacent end of the chain being then preferably connected to one of the angle iron members 15, 16, as indicated at 46. It will be noted that the chain passes around sheave 39 in the same direction as that in which it passes around sheave 37, as clearly shown in Fig. 2.

70 The operation of the hoisting mechanism is as follows: To hoist the load, the sheave 21 is rotated in a clockwise direction as viewed in Fig. 2, as indicated by the arrow thereon, thereby drawing down the right-hand course of the chain as viewed in said figure, and paying out the left hand course thereof. The travel of the chain over sheave 37 causes said sheave to rotate in the same direction as the sheave 21, and through the spring 40 applies power to the sheave 39, which causes it also 75 to rotate in the same direction. Consequently the latter sheave takes up the chain paid out by the sheave 21 and delivers it at the right-hand side of said sheave as viewed in Fig. 2, so that it hangs as a loop from the point 46. 80 The bight of the chain between the sheaves 37, 39 and the sheave 21 is therefore always held taut. The sheave 43 serves to guide the chain so that it properly engages the sheave 39. In lowering the load all the sheaves are 85 rotated in the opposite direction by its weight, but in lowering the chain when it carries no load the sheave 21 is rotated in a counterclockwise direction by power, and the consequent downward pull on the left-hand course of the chain as viewed in Fig. 2, 90 positively rotates the sheave 39 in a counterclockwise direction, which, through the spring 40, rotates the sheave 37 in a like direction, thereby drawing up the right-hand course of the chain and lowering the load 95 sustaining end thereof. Our improved construction, therefore, provides for positively moving the chain in either direction, regardless of whether or not it carries a load, and 100 always maintains the bight of the chain taut so that any stretching of the chain is compensated for and it properly engages the several sheaves at all times. Furthermore, 105 there is no slack to hang down and interfere with the travel of the tractor, so that our improved construction is peculiarly suitable for use in connection with portable cranes. It will also be observed that by virtue of the 110 substantially irreversible action of the worm wheel 28 and worm 30 (which prevents the worm wheel from driving back through the worm) these two elements serve to lock the hoisting mechanism with its load in any elevated position.

115 In the embodiment of our invention shown and described the sheaves are designed to receive and cooperate with a hoisting chain, but we wish it to be understood that our invention also contemplates the use of any other 120 125 130

suitable flexible hoisting element designed to cooperate with supporting sheaves without slippage, and, therefore, the term "chain" as herein used should be construed accordingly. 5 Also, while we have shown our invention as applied to a shop tractor in which the hoisting mechanism is adapted to be operated by power derived from the engine of the tractor, it is to be understood that our improved 10 hoisting mechanism may be operated by hand as well as by power, and that it is not limited to use with a tractor as shown, but is adapted to be used in any other situation for which it is suitable. Furthermore, our invention is 15 not restricted to the specific construction shown and described, except in so far as details of construction are particularly claimed.

What we claim as our invention and desire to secure by Letters Patent, is—

20 1. A hoisting mechanism comprising a hoisting chain, an upper sheave over which the load carrying portion of said chain operates, a driving sheave around which a bight of said chain runs and by which said chain is driven, and means actuated by the travel 25 of the chain to maintain both sides of said bight taut relatively to said driving sheave.

2. A hoisting mechanism comprising a hoisting chain, an upper sheave over which the load carrying portion of said chain operates, a driving sheave around which a bight of said chain runs and by which said chain is driven, and means actuated by the travel 30 of the hoisting chain in either direction to maintain both sides of said bight taut relatively to said driving sheave.

3. A hoisting mechanism comprising a hoisting chain, an upper sheave over which the load carrying portion of said chain operates, a driving sheave around which a bight of said chain runs and by which said chain is driven, means actuated by the travel 40 of the chain to maintain both sides of said bight taut relatively to said driving sheave, and means for operating said driving sheave.

4. A hoisting mechanism comprising a hoisting chain, an upper sheave over which the load carrying portion of said chain operates, a driving sheave around which a bight 50 of said chain runs and by which said chain is driven, an intermediate sheave over which one course of the chain travels between said sheaves, and means actuated by the rotation of said intermediate sheave in hoisting to maintain both sides of the bight of said chain taut relatively to said driving sheave.

5. A hoisting mechanism comprising a hoisting chain, an upper sheave over which the load carrying portion of said chain operates, a driving sheave around which a bight 60 of said chain runs and by which said chain is driven, an intermediate sheave over which one course of the chain travels between said sheaves, and a sheave, over which a bight of the chain travels, associated with said inter-

mediate sheave and cooperating therewith to maintain both sides of the bight of the chain taut relatively to said driving sheave.

6. A hoisting mechanism comprising a hoisting chain, an upper sheave over which the load carrying portion of said chain operates, a driving sheave around which a bight of said chain runs and by which said chain is driven, an intermediate sheave over which one course of the chain travels between said sheaves, and a sheave, over which a bight 70 of the chain travels, associated with said intermediate sheave and cooperating therewith to maintain both sides of the bight of the chain taut relatively to said driving sheave 75 when the chain travels in either direction.

7. A hoisting mechanism comprising a hoisting chain, an upper sheave over which the load carrying portion of said chain operates, a driving sheave around which a bight of said chain runs and by which said chain is driven, an intermediate sheave over which one course of the chain travels between said sheaves, a second intermediate sheave, over which a bight of the chain travels, associated 80 with and rotatable relatively to said first intermediate sheave and cooperating therewith to maintain both sides of the bight of the chain taut relatively to said driving sheave 85 when the chain travels in either direction, and a spring interposed between said intermediate sheaves for transmitting power from one of said sheaves to the other.

8. A crane attachment comprising a supporting frame, a mast carried thereby, a sheave mounted on the mast, a driving sheave supported by said frame, a chain having a bight thereof looped around said driving sheave and having a load carrying portion operating over said first-mentioned sheave, means for driving said driving sheave, and means for maintaining both sides of the bight of said chain taut relatively to said driving sheave. 100

9. A crane attachment comprising a supporting frame, a mast carried thereby, a sheave mounted on the mast, a driving sheave supported by said frame, two intermediate sheaves, and a spring for transmitting power 105 from either of said intermediate sheaves to the other.

10. A crane attachment comprising a supporting frame, a mast carried thereby, a sheave mounted on the mast, a driving sheave supported by said frame, two intermediate sheaves, a spring for transmitting power 120 from either of said intermediate sheaves to the other, and a hoisting chain running over said first-mentioned sheave and one of said intermediate sheaves and having bights looped around said driving sheave and the other of said intermediate sheaves.

11. A hoisting mechanism comprising a hoisting chain, an upper sheave over which the load carrying portion of said chain oper- 130

ates, a driving sheave around which a bight of said chain runs and by which said chain is driven, means actuated by the travel of the chain to maintain both sides of said bight taut relatively to said driving sheave, and worm gear mechanism for operating said driving sheave.

12. A crane attachment comprising a supporting frame, a mast carried thereby, a sheave mounted on the mast, a driving sheave supported by said frame, a chain having a bight thereof looped around said driving sheave and having a load carrying portion operating over said first-mentioned sheave, worm gear mechanism for driving said driving sheave, and means for maintaining both sides of the bight of said chain taut relatively to said driving sheave.

13. A crane attachment comprising a supporting frame, a mast carried thereby, an upper sheave mounted on the mast, a driving sheave supported by said frame in alinement with said first mentioned sheave, a pair of intermediate sheaves between said upper sheave and said driving sheave, a laterally extending lug on one of said intermediate sheaves, a spring bearing at one end on said lug, a laterally extending lug on the other of said intermediate sheaves on which the other end of said spring bears, whereby power is transmitted from either of said intermediate sheaves to the other.

14. A crane attachment comprising a supporting frame, a mast carried thereby, an upper sheave mounted on the mast, a driving sheave supported by said frame in alinement with said upper sheave, a pair of intermediate sheaves between said upper sheave and said driving sheave, a laterally extending lug on one of said intermediate sheaves, a spring bearing at one end on said lug, a laterally extending lug on the other of said intermediate sheaves on which the other end of said spring bears, whereby power is transmitted from either of said intermediate sheaves to the other, and a hoisting chain running over said upper sheave and one of said intermediate sheaves and having bights looped around said driving sheave and the other of said intermediate sheaves.

15. A crane attachment comprising a supporting frame, a mast carried thereby, an upper sheave mounted on the mast, a driving sheave supported by said frame in alinement with said upper sheave, a pair of intermediate sheaves between said upper sheave and said driving sheave, one of said intermediate sheaves being alined with said upper and driving sheaves, a laterally extending lug on said alined intermediate sheave, a spring bearing at one end on said lug, and a laterally extending lug on the other of said intermediate sheaves on which the other end of said spring bears, whereby power is transmitted

from either of said intermediate sheaves to the other.

16. A crane attachment comprising a supporting frame, a mast carried thereby, an upper sheave mounted on the mast, a driving sheave supported by said frame in alinement with said upper sheave, an intermediate sheave between said upper and driving sheaves and in alinement therewith, another intermediate sheave mounted coaxially with said first mentioned intermediate sheave, a guide sheave supported by said frame in alinement with said latter intermediate sheave, and a spring for transmitting power from either of said intermediate sheaves to the other.

17. A crane attachment comprising a supporting frame, a mast carried thereby, an upper sheave mounted on the mast, a driving sheave supported by said frame in alinement with said upper sheave, an intermediate sheave between said upper and driving sheaves and in alinement therewith, another intermediate sheave mounted coaxially with said first mentioned intermediate sheave, a guide sheave supported by said frame in alinement with said latter intermediate sheave, a spring for transmitting power from either of said intermediate sheaves to the other, and a hoisting chain running over said upper sheave and said first-mentioned intermediate sheave and having bights looped around said driving sheave and the latter intermediate sheave, said guide sheave guiding the hoisting chain to said latter intermediate sheave.

18. A crane attachment comprising a frame adapted to be attached to a vehicle, a mast carried by said frame, a hoisting chain, a sheave mounted on the mast, over which the load carrying portion of said chain operates, a driving sheave supported by said frame, around which a bight of said chain runs and by which said chain is driven, means actuated by the travel of the chain to maintain both sides of said bight taut relatively to said driving sheave, and means mounted on said frame and adapted to be driven from the vehicle for operating said driving sheave.

19. A crane attachment comprising a frame adapted to be attached to a vehicle, a mast carried by said frame, a sheave mounted on the mast, a driving sheave supported by said frame, two intermediate sheaves, a spring for transmitting power from either of said intermediate sheaves to the other, a hoisting chain running over said first-mentioned sheave and one of said intermediate sheaves and having bights looped around said driving sheave and the other of said intermediate sheaves, and means mounted on said frame and adapted to be driven from the vehicle for operating said driving sheave.

20. A crane attachment comprising a frame adapted to be attached to a vehicle, a

mast carried by said frame, a hoisting chain, an upper sheave mounted on the mast, over which the load carrying portion of said chain operates, a driving sheave around which a bight of said chain runs and by which it is driven, means actuated by the travel of the chain to maintain both sides of said bight taut relatively to said driving sheave, and worm gear mechanism mounted on said frame and adapted to be driven from the vehicle for operating said driving sheave.
